Primary Examiner — Eliza Z Harvey*Assistant Examiner* — Kayla Marie Bennett(74) *Attorney, Agent, or Firm* — Lee & Hayes, P.C.(57) **CLAIM**

The ornamental design for a furniture floor protector, as shown and described.

DESCRIPTION

FIG. 1 is a perspective view of our new furniture floor protector design;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a rear view thereof;

FIG. 8 is a perspective view of the furniture floor protector shown in an environment of use; and,

FIG. 9 is a perspective view of the furniture floor protector shown in an alternate environment of use.

The broken lines shown are included only for the purpose of illustrating environmental subject matter, and form no part of the claimed design.

1 Claim, 6 Drawing Sheets(56)
